SANITARY SANDWICH ENVELOPE

James Nagle, Glendale, N. Y.

Application July 23, 1937, Serial No. 155,326

3 Claims. (Cl. 229—53)

The present invention relates to a sanitary sandwich envelope in which sandwiches or other foods can be placed for the purpose of serving them.

5 It is an object of the invention that individual cut pieces of pie, cake, or other foods be served in my novel sanitary envelope without contaminating the same and without soiling the hands or clothing.

10 The various novel features of the invention by which the foregoing and other desirable objects are attained are set forth in the following specification, illustrated in the accompanying drawing, and broadly covered in the claims.

15 Figure 1 is a perspective view of the sanitary sandwich envelope.

Figure 2 is a side elevational view of the sanitary sandwich envelope.

20 Figure 3 is a plan view of the sanitary sandwich envelope.

Figure 4 is a plan view of a blank from which the sanitary sandwich envelope is formed.

25 Figure 5 is a view of the blank on a reduced scale as disclosed in Figure 4, and being partly folded.

The sanitary sandwich envelope is indicated by the numeral 10, which as disclosed in Figure 1, has four triangular sides and two narrow rectangular sides, and all of the sides of the envelope 30 tapering to one end 12.

The sanitary sandwich envelope 10 is made from a flat foldable blank as disclosed in Figure 4, and comprises triangular-shaped panels, 14, 16, 18, and 20. The triangular-shaped panels 14 and 16 are spaced adjacent each other and being joined by the folding line 22. The triangular-shaped panels 18 and 20 are contiguous to each other and are joined by the folding line 24. The triangular-shaped panels 16 and 18 are respectively joined by the folding lines 26 and 28 to the narrow rectangular-shaped panel 30.

40 The panel 20 is joined by a folding line 32 to a narrow rectangular-shaped panel 34, and panel 14 is joined by a folding line 36 to a narrow rectangular-shaped panel 38. A small triangular tab 40 is joined by a folding line 42 to the end of the rectangular panel 38. A central triangular tab 44 is joined respectively by folding lines 46 and 48 to the tab 40 and the rectangular panel 50, and a substantially triangular-shaped tab 50 is joined by folding lines 52 and 54 respectively to the tab 44, and the rectangular panel 34.

45 Adhesive material 37 is applied to the panel 38 and the tab 40, so that when the blank 11 is folded, 55 it can be sealed together. In folding the blank

11, the panels 34 and 20 are folded over so that panel 34 overlies panel 30, and panel 20 overlies panel 18, and at the same time tab 50 will overlie the tab 44. Then panels 38 and 14 are folded so that panel 38 overlies panel 34, and panel 14 overlies panel 16, and at the same time tab 40 overlies tab 50. The panel 38 is sealed to the outside of the panel 34 and tab 40 is sealed to the tab 50. The composite triangular tab 51, which has been formed from the tabs 40, 44 and 50 being folded as indicated above, is folded over the rectangular panel 38 as shown in Figure 1. The composite tab 51 is then sealed to the panel 38 by adhesive.

10 The sanitary sandwich envelope is now opened up as disclosed in Figure 1. The envelope is open 15 at the top, and is a six sided container, with all of the sides tapering toward one end 12. The envelope has a wide opening due to the two narrow rectangular panels being opposite each other and two of the triangular panels being of larger 20 area than the rectangular panels being adjacent and situated opposite the other two triangular panels of the same area which are also adjacent to each other. The envelope 10 being of a tapering shape, will conveniently hold a slice of pie, 25 cake or a sandwich, which are usually cut in triangular shapes.

The material of my novel sanitary sandwich envelope may be wax paper, cardboard, or the like. It is preferably made from light weight 30 paper which is inexpensive, but at the same time durable enough to serve as a sandwich container.

The present sanitary envelope is used primarily as a container in curb service or the so called take out service which is now so prevalent.

35 The drawing illustrates the possible embodiment of the invention, while modifications and changes may be made which come within the true spirit and broad scope of the invention.

I claim:

40 1. A blank, comprising a rectangular panel, triangular panels of greater area joined by folding lines to the said rectangular panel, a triangular panel of substantially the same area joined by folding lines to each of the first-mentioned 45 triangular panels, narrow rectangular panels joined by folding lines to each of the second-mentioned triangular panels, triangular tabs joined by folding lines to the first-mentioned rectangular panel and the second-mentioned 50 rectangular panels, and the said triangular tabs joined together by folding lines.

45 2. A sanitary food envelope and the like comprising a rectangular panel, a triangular panel of greater area joined by folding lines to opposite 55

- sides of the said rectangular panel, a triangular panel of substantially the same area joined by folding lines to each of the first-mentioned triangular panels, narrow rectangular panels joined by folding lines to each of the second-mentioned triangular panels, tabs joined by folding lines to the first-mentioned rectangular panel and the second-mentioned rectangular panels, and the said tabs being joined together by folding lines,
- 5 10 one of the narrow rectangular panels and its attached triangular panel being folded to overlie the said rectangular panel and the triangular panel adjacent the said attached triangular panel respectively, and the tab of the first-mentioned narrow rectangular panel being folded to overlie the tab of the rectangular panel, the second narrow rectangular panel and its attached triangular panel being folded to overlie the first folded narrow rectangular panel and the triangular panel adjacent the second-mentioned attached triangular panel respectively, and the tab of the second folded narrow rectangular panel being folded to overlie the tab of the other narrow rectangular panel, the second folded narrow rectangular panel
- 15 20 25 and its tab portion being adhesively secured to the first folded narrow rectangular panel and its tab portion respectively, and the overlapping tab portions being folded and adhesively secured to the second folded narrow rectangular panel thereby forming a six sided distended envelope of open form tapering to a bottom closure.
- 30 3. A sanitary food envelope and the like comprising a rectangular panel, a triangular panel joined by folding lines to opposite sides of the

said rectangular panel, a triangular panel joined by folding lines to each of the first-mentioned triangular panels, narrow rectangular panels joined by folding lines to each of the second-mentioned triangular panels, triangular tabs joined by folding lines to the first-mentioned rectangular panel and the second-mentioned rectangular panels, and the said triangular tabs being joined together by folding lines, one of the narrow rectangular panels and its attached triangular panel being folded to overlie the said rectangular panel and the triangular panel adjacent the said attached triangular panel respectively, and the tab of the first-mentioned narrow rectangular panel being folded to overlie the triangular tab of the rectangular panel, the second narrow rectangular panel and its attached triangular panel being folded to overlie the first folded narrow rectangular panel and the triangular panel adjacent the second-mentioned attached triangular panel respectively, and the triangular tab of the second folded narrow rectangular panel being folded to overlie the triangular tab of the other narrow rectangular panel, the second folded narrow rectangular panel and its triangular tab portion being adhesively secured to the first folded narrow rectangular panel and its triangular tab portion respectively, and the overlapping triangular tab portions being folded and adhesively secured to the second folded narrow rectangular panel thereby forming a six sided distended envelope of open form tapering to a bottom closure.

JAMES NAGLE.
